UNITED STATES PATENT OFFICE.

SOPHUS NYBOE, OF BROOKLYN, NEW YORK.

COLLAPSIBLE LIFE-BOAT.

1,062,181.

Specification of Letters Patent. Patented May 20, 1913.

Application filed January 13, 1913. Serial No. 741,677.

To all whom it may concern:

Be it known that I, SOPHUS NYBOE, a citizen of the Danish Monarchy, and a resident of Brooklyn, Kings county, New York, 5 have invented certain new and useful Improvements in Collapsible Life-Boats, of which the following is a specification.

This invention relates to improvements in collapsible lifeboats, and the object of the 10 invention is to provide a life boat of novel, practical and improved construction adapted to be easily and quickly unfolded in an emergency.

One object of the invention is to provide 15 a boat adapted to be folded into a compact form so as to occupy but little space.

Another object is to provide a construction whereby a continuous air chamber is formed along the keel of the boat when it 20 is unfolded.

Other objects will appear as this specification proceeds.

In the drawings illustrating the invention 25 Figure 1 is a plan view of a collapsible life boat embodying the invention. Fig. 2 is a view on line 2—2 of Fig. 1. Fig. 3 is a view on line 3—3 of Fig. 1. Fig. 4 is a view similar to Fig. 3 but showing the boat collapsed. Fig. 5 is a plan view showing the boat col- 30 lapsed. Fig. 6 is a detail view on line 6—6 of Fig. 3, and Fig. 7 is a detail view on line 7—7 of Fig. 3.

I construct my lifeboat of any suitable material. Either wood or canvas made wa- 35 terproof, or of metal made rustproof, or I may use a combination of these or other ma- terials. The boat consists of two symmetri- cal halves adapted to fold along the keel. The two main parts of the boat are the sides 40 10, 10 suitably shaped so as to form the boat shell when folded out. The sides are hinged to one another along the keel line by a plu- rality of hinges 11 suitably secured to the sides by rivets or other fastening means. It 45 will be understood that I intend to make these hinges 11 of sufficient weight to form a proper keel for the boat. For purposes of air- and water-tightness there is provided a packing 12, indicated in black in Figs. 6 50 and 7 and seen in section in Fig. 2. This packing is preferably in the form of a continuous strip of rubber or similar packing material which is laid between the hinges and the sides 10 as shown. A portion of 55 the packing 13 is turned up over the ends of the sides and carried down inside the boat

below the fore and aft decks as a matter of precaution.

14 is the gunwale or railing for strength- 60 ening and stiffening the sides.

The boat is provided with one or more seats each of which consists of two parts 15, 15 hinged together in the center by hinges 16 and hinged to the sides of the boat by hinges 17. A false bottom is provided a dis- 65 tance above the keel and comprises the two parts 18, 18 hinged together in the center by hinges 19 and hinged to the sides 10 by hinges 20.

A short deck is provided at each end of 70 the boat. Each deck comprises the two symmetrical parts or halves 21, 21 hinged together in the center by hinges 22 and hinged to the sides of the boat by hinges 23. As best seen in Fig. 6 the deck portions 21, 75 21 are each provided with a depending flange 24.

Vertical walls or partitions are provided 80 to separate the space under the decks from the interior of the boat. Each wall com- 85 prises two parts 26, 26 hinged like doors to the sides of the boat by hinges 27 and hinged together in the center by hinges 28. The hinges 27 and 28 are spring hinges having springs 29 inserted in known manner. The 85 tendency of the springs is to keep the partitions vertical and closed as shown in Fig. 7, which illustrates one of the walls in plan view and section.

For the purposes of air-tightness and wa- 90 ter-tightness all edges and abutting surfaces of the various members described are pro- 95 vided with packing strips 30 such as seen in Figs. 6 and 7. Preferably the strips are set in suitable grooves. Suitable packing will 95 also be employed around the hinges.

The boat is provided with oarlocks 31 and eyes 32. The latter for the use of the ropes with which the boat is lowered, and when the boat is collapsed, chains or other 10 means may be passed through the eyes to prevent the boat from unfolding.

33 is a ring secured to one of the bottom parts 18.

From the foregoing it will be apparent 10 that when unfolded there is provided an air chamber 35 in the bottom of the boat and large air chambers 36 at either end under the decks and that these air chambers are all in communication. They assist in keeping 11 the boat afloat.

Where the boat is unfolded as in Figs. 1

to 3, the decks, partitions, seats and the bottom aforesaid are folded out straight and as they are nicely fitted in the boat they exert a pressure on the sides thereof, preventing accidental collapse. The springs 29 assist in keeping the partitions 26, 26 in line and also press them against the packings 30 in the depending flanges 24 of the decks and the packings 30 in the ends of the bottom as shown in Fig. 6. The walls "break" in the direction of the arrows in Fig. 7, that is, they fold outward toward the ends of the boat. To prevent any accidental "break" of the walls 26 I may provide each 15 one with a latch 40 as shown in Fig. 3.

Normally the boat is collapsed as seen in Figs. 4 and 5 from which it will be clear that the bottom, the seats and the decks fold upwardly and the walls 26 fold endwardly 20 of the boat as already explained. This folding of the aforesaid parts permits the sides of the boats to be closely folded together along the keel line so that the folded boat occupies but very little space.

When unfolding the boat, the sides are 25 pulled apart and the seats, decks and bottom pressed down and straightened out. The walls 26 straighten automatically by the springs 29. The natural pressure of 30 the occupants tends to keep the parts straightened and the boat unfolded. The ring 33 is for the purpose of folding up the bottom.

It will be seen that the boat comprises 35 practically two symmetrical halves adapted to fold along the centerline of the boat so as to occupy but little space and which are also adapted to be quickly unfolded for use. Further, that the decks, walls 26 and the 40 bottom provide a protection against injury to the sides and at the same time keep the sides apart and form the air chamber referred to.

Various changes in the detailed construction 45 may be made without departing from the spirit of the invention and within the scope of the appended claims.

I claim:

1. In a collapsible boat the combination of 50 two sides, a plurality of hinges for hinging the said two sides together, the said hinges forming a keel, a packing member interposed between said hinges and the said sides, deck members and bottom members hinged 55 to the said sides and adapted to be folded upwardly in the center and vertical collapsible partition members hinged to the said sides and extending from the said deck members to the said bottom members and 60 adapted to be folded endwise of the boat.

2. In a collapsible boat the combination of 65 two sides, means for folding the same together along the keel line of the boat, collapsible deck members and collapsible bottom members hinged to the said sides, collapsible

vertical partition members hinged to the sides of the boat and extending from the said deck members to the said bottom members, air-tight joint between all of the abutting edges of all of the aforesaid members whereby an air chamber is formed between the sides of the boat and the said deck members, bottom members and vertical partition members. 70

3. In a collapsible boat the combination of 75 two non-collapsible sides, means for folding the same together along the keel line, a collapsible deck at each end of the said boat, a collapsible bottom and vertical collapsible partitions for separating the space below 80 the said decks and the said bottom from the interior of the boat.

4. In a collapsible boat the combination of 85 two non-collapsible sides, a plurality of hinges secured to said sides along the keel lines thereof, a deck member, a bottom member and a vertical partition member hinged to each of the said sides, all the said members on the one side of the boat being hinged to the corresponding members on the opposite side of the boat, whereby when the said sides are folded together along the keel line, the said deck and bottom members fold upwardly between the sides and the said partition members fold endwise of the boat below 95 the said deck members.

5. In a collapsible boat the combination of 100 two sides adapted to be folded together, deck members secured at each end of the boat to the sides thereof, said deck members having a depending flange, vertical partitions secured to the sides of the boat below said deck members and extending from the latter to the bottom of the boat and means for forcing the upper edge of said partition members against the said depending flanges whereby an air-chamber is formed between the deck members and the sides of the boat. 105

6. In a collapsible boat the combination of 110 two sides, a deck at each end of the boat, a false bottom, vertical partitions extending between the said decks and the said bottom, the said two sides, the decks, the bottom and the partitions being adapted to be folded together along the longitudinal axis of the boat. 115

7. In a collapsible boat the combination of 120 two sides adapted to be folded along the keel line, a deck at each end of the boat comprising two deck members, a false bottom in the boat comprising two bottom members extending between the said decks, two vertical partitions extending from the decks to the said bottom at each end of the latter, each partition comprising two partition members, all of the aforesaid members being hinged together in the center of the boat and to the sides thereof whereby the said decks and the bottom fold upwardly between the sides when the boat is collapsed 125 130

and the said partitions fold endwise of the boat below the decks.

8. In a collapsible boat the combination of two sides hinged together along the keel line, a deck at each end of the boat, a bottom extending between said decks, vertical partitions between the decks and the bottom whereby an air chamber is formed below the said decks and the said bottom.

10 9. In a collapsible boat the combination of two sides, a deck member, a vertical parti-

tion member, a bottom member and seat members hinged to each of the said sides and means for folding the sides and all of the aforesaid members along the longitudinal axis of the boat to collapse the same. 15

Signed at New York, N. Y. this 10th day of January 1913.

SOPHUS NYBOE.
